UNITED STATES PATENT OFFICE.

CLARENCE C. FLATT, OF DES MOINES, IOWA.

DESIGN FOR A STORE FRONT.

Application filed July 11, 1928. Serial No. 27,451. Term of patent 14 years.

To all whom it may concern:

Be it known that I, CLARENCE C. FLATT, a citizen of the United States, and a resident of Des Moines, in the county of Polk, and State of Iowa, have invented a certain new, original, and ornamental Design for a Store Front, of which the following is a specification, reference being had to the accompanying drawing forming part thereof.

I claim:

The ornamental design for a store front, as shown.

Des Moines, Iowa, June 13, 1928.

CLARENCE C. FLATT.
